UNITED STATES PATENT OFFICE

JOHN N. HELTZEL, OF WARREN, OHIO

JOINT-PRODUCING MACHINE

Application filed April 28, 1929, Serial No. 358,330.

The present invention relates to joint machines, for installing joints in concrete roads, pavements, and the like, and the invention aims to provide a novel and improved machine of that kind.

Another object of the invention is the provision of a joint machine comprising joint installing means movably mounted on a carriage to be moved along a predetermined line 10 for producing the joint.

With the foregoing and other objects in view, which will be apparent as the description proceeds, the invention resides in the construction and arrangement of parts, as 15 hereinafter described and claimed, it being understood that changes can be made within the scope of what is claimed, without departing from the spirit of the invention.

The invention is illustrated in the accompanying drawings, wherein—

Figure 1 is a plan view of the improved machine.

Fig. 2 is an enlarged cross section on the line 2—2 of Fig. 1.

Fig. 3 is a vertical section on the line 3—3 of Fig. 2.

Figs. 4 to 8, inclusive, are cross-sectional details showing the steps in the building of the joint.

Fig. 9 is a cross sectional detail illustrating a modified form of joint.

Fig. 10 is a cross sectional detail illustrating a modified form of device for producing the groove or cleft in the plastic concrete.

Fig. 11 is a perspective view of the blade or tool shown in Fig. 10.

Fig. 12 is an end view of a modified form of grooving device, showing the guide rail of the carriage in cross section.

Fig. 13 is a side elevation of the device shown in Fig. 12.

Fig. 14 is an end view of another modification in the grooving device.

Fig. 15 is a side elevation thereof.

The machine comprises a suitable carriage or bridge 1 having the wheels 2 to move on the side forms or rails 3 between which the road or pavement is built, and said carriage has parallel longitudinal rails 4 disposed at 50 opposite sides of the line of the joint.

The carriage also has platforms 5 at the outer sides of the rails 4, and transverse platforms 6 on which the workmen may be supported while building the joint.

A secondary carriage 7 is mounted on the main carriage or frame, and has the transverse axles 8 on which wheels 9 are adjustable transversely, said wheels rolling on the rails 4.

In order to hold the carriage 7 down on the rails, it has hangers 10 provided with rollers 11 moving under flanges 12 of the rails 4, thereby preventing the carriage 7 from tipping or raising off the rails 4.

The joint installer or grooving device comprises a trowel or plate 13 having an upturned margin, and a grooving blade 14 depends from the plate 13 to form the groove in the plastic concrete. The plate 13 has upstanding stems 15 and 16 slidable in the carriage 7, and coiled springs 17 surround said stem and are confined between said carriage 7 and nuts 18 adjustable on the stems, in order that the springs will carry the weight of the plate 13 and sleeve 14 and to lift them, when free, from the concrete.

The rear stem 16 has a handle 19 at its upper end to be conveniently grasped by the workman for reciprocating the carriage 7 and depressing the rear portion of the grooving device.

A lever 20 is pivoted on the frame of the carriage 7 and has a cam 21 seating on a head 22 with which the forward stem 15 is provided, for depressing said stem. A rod 23 is connected to the lever 20 and extends rearwardly over the handle 19 in order that the lever 20 may be conveniently operated.

In forming the groove the carriage 7 is reciprocated on the rails 4, with the blade 14 depressed into the plastic concrete. The forward and backward motion of the blade will provide momentum to force the forward end of the blade into the material, and the trowel or plate 13 smooths the surface of the material at the opposite sides of the groove.

The trowel 13 and blade 14 may be vibrated in order to more effectively enable the blade to cut into the plastic concrete. This vibratory motion of the blade is conveniently 100

produced by an engine 24 mounted on the trowel 13 and having an unbalanced fly-wheel.

The grooving device is reciprocated while the main carriage or frame 1 is stationary, and said carriage 1 may be advanced as the groove is completed between the rails 4.

The steps in the method of installing the joint are shown in Figs. 4 to 8, inclusive. A groove 25 is first produced in the plastic concrete, such as by the means disclosed in my copending applications Serial No. 6,806, filed Feb. 4, 1925, Serial No. 24,801, filed April 21, 1925 and Serial No. 223,161, filed September 30, 1927. This preliminary groove is produced first while the material is poured and finished or shortly thereafter, so as to separate the stones, broken rock or coarser aggregate along the line of the joint. The cement and sand may flow back into the groove, as seen at 26 in Fig. 5, but the coarser aggregate remains separated.

The blade 14 subsequently reopens the groove 25 by displacing the finer material, the coarser aggregate previously having been displaced so as not to interfere with the movement of the blade 14.

The reenforcing or transverse tie rods 27 are below the groove 25, and may be forced down when said groove is formed. The blade on the road finishing machine (not shown) which first forms the groove or which divides the coarser aggregate may depress the reinforcement or rods 27 as well as deflecting the coarser aggregate to opposite sides.

When the groove is reopened by the blade 14 a form 28 may be inserted in the groove, as seen in Fig. 7, to hold the groove open while the concrete sets, and may be subsequently removed to fill the groove with tar, asphalt or other sealing material, as seen at 29 in Fig. 8. It is also possible to insert joint strips into the groove, which strips may be of metal, premolded material, or the like. Fig. 9 illustrates a premolded strip 29' of asphalt or other composition.

When operating the blade 14 to reopen the groove, the handle 19 may be depressed to depress the rear end of the blade, while the forward end thereof is raised, which is desirable when the concrete is set slightly. If it is desired to place additional pressure on the forward end of the blade, the cam 21 is turned to depress the forward end of the blade. The vibratory means or engine 24 is of especial advantage when working in semi-set or partially hardened concrete.

When the concrete is of the right consistency, the joint form or plate 28 (Fig. 7) will not be required for producing an open joint or groove, said form only being used when the material is too soft or plastic, or when weather conditions are such that the setting of the concrete is slowed down. In extremely hot weather, or when mixtures are used to

produce a quick setting of the concrete, then the open groove produced by the blade 14 will remain open without using the form 28.

Figs. 10 and 11 illustrate a simple grooving device or tool having the blade 14' movable between parallel rails 4' to reopen the groove or to produce a cleft in the plastic concrete. The blade has a handle 19' and has rollers 9' to move on the rails 4', so that the tool may be conveniently reciprocated by hand to form or reopen the groove.

Figs. 12 and 13 illustrate a modification wherein a single rail 4" is used for guiding the carriage 7". The rail is of I-section as shown, and the wheels 9" of the carriage move on one flange of the rail. The carriage has rollers 11" engaging under the rail to hold the carriage on the rail.

The trowel or plate 13" is suspended from the carriage and has the blade 14", and a handle 19" is pivoted to said trowel for reciprocating same conveniently from the workman's platform 5". The rail 4" may be adjustable transversely and vertically in order to properly position the tool.

Figs. 14 and 15 illustrate another modification, wherein the carriage 7" has wheels 9" moving on the rail 4" and wheels or rollers 11" moving under said rail. Vertical screws 21" are mounted on the carriage 7" for adjusting bearings 22" vertically, and arms 15" are hingedly connected with said bearings and have slots 30 receiving clamping bolts or elements 31 which fasten the trowel 13" to said arms, thereby permitting of transverse adjustment of the trowel 13" and blade 14" with respect to the rail 4".

The bearings 22" may be adjusted vertically by rotating the screws 21" in order to properly position the trowel on the plastic concrete.

A handle 19" is pivotally connected to the trowel 13" for conveniently reciprocating same.

Having thus described the invention, what is claimed as new is:

1. A joint machine comprising a carriage movable longitudinally over plastic concrete, joint producing means, and means supporting said means from the carriage for movement longitudinally of the carriage in the same direction that the carriage is movable.

2. A joint machine comprising a carriage movable longitudinally over plastic concrete and having longitudinal guiding means extending parallel to the direction of movement of the carriage, and joint producing means movable along said guiding means.

3. A joint machine comprising a carriage movable longitudinally over plastic concrete and having a longitudinal rail extending parallel to the direction of movement of the carriage, and joint producing means movable along said rail.

4. A joint machine comprising a carriage and a joint producing tool mounted for re-

ciprocatory movement on the carriage in the same direction that the carriage is movable and having a trowel and a depending blade.

5. A joint machine comprising a carriage, a joint producing tool mounted for reciprocatory movement on the carriage in the same direction that the carriage is movable and having a trowel and a depending blade, and means for vibrating said tool.

10 6. A joint machine comprising a carriage, a guide supported by the carriage and extending parallel to the direction of movement of the carriage, a joint producing blade, and means supporting said blade for movement

15 from said guide.

7. A joint machine comprising a carriage, a guide supported by the carriage and extending parallel to the direction of movement of the carriage, a joint producing blade, and means adjustably supporting said blade from

20 said guide for movement along the guide.

8. A joint machine comprising a carriage, a secondary carriage mounted for movement thereon in the same direction that the first

25 named carriage is movable, a joint producing

tool, and means supporting said tool from

the secondary guide for vertical movement.

9. A joint machine comprising a carriage, a secondary carriage mounted for movement

30 thereon in the same direction that the first

named carriage is movable, a joint producing

tool connected with the secondary carriage

for vertical movement, and means for de-

pressing said tool.

35 10. A joint machine comprising a carriage, a secondary carriage mounted for movement thereon in the same direction that the first named carriage is movable, a joint producing tool connected with the secondary carriage

40 for vertical movement, spring means on the

secondary carriage for yieldingly raising the

tool, and means for depressing said tool.

11. A joint machine comprising a carriage, a secondary carriage mounted for movement

45 thereon in the same direction that the first

named carriage is movable, a joint producing

tool having forward and rear upstanding

stems slidable in the secondary carriage, and

individual means for depressing either stem.

50 12. A joint machine comprising a carriage, a joint producing tool having forward and rear upstanding stems slidable in the carriage, spring means on the carriage for yield-

ably raising each stem, and individual means

55 for depressing either stem.

13. A joint machine comprising a carriage having a guide arranged parallel to the line of movement of the carriage, a joint producing tool supported for movement from said guide, and a handle connected to said tool.

60 14. A joint machine comprising a carriage movable longitudinally over a road under construction and having spaced parallel lon-

65 gitudinal rails parallel to the direction of

movement of the carriage, and joint produc-

ing means movable between said rails.

In testimony whereof I hereunto affix my

signature.

JOHN N. HELTZEL. 70
